UNITED STATES PATENT OFFICE.

JOHN Q. C. SEARLE, OF CHICAGO, ILLINOIS.

CAR AND HOUSE WARMER.

SPECIFICATION forming part of Letters Patent No. 340,825, dated April 27, 1886.

Application filed December 3, 1883. Serial No. 113,480. (No model.)

To all whom it may concern:

Be it known that I, JOHN Q. C. SEARLE, of Chicago, in the county of Cook and State of Illinois, have invented certain new and useful 5 Improvements in Car and House Warmers, of which the following is a specification.

My invention relates to hot-water warming apparatus for railway-coaches and other purposes, and is in the nature of an improvement 10 upon a certain invention for which Letters Patent of the United States were granted to me January 18, 1881.

My invention has for its object the construction of certain special fittings for the connection of the heating-coil and several members 15 of the system of circulation hot-water pipes, whereby the operation of the apparatus and the warming of the coach are materially improved; and it consists in the novel construction and combinations of parts hereinafter described, and particularly pointed out in the claims.

In the accompanying drawings, Figure 1 is an interior view of one end of a railway passenger-coach. Figs. 2 and 3 are vertical sections through the "special" T's. Fig. 4 is a vertical section through the bifurcated fitting. Fig. 5 is a vertical section through a special "cross;" and Fig. 6 is a vertical section through 20 a building, showing the application of certain portions of my present improvement to the warming of houses.

Similar letters of reference indicate similar parts.

35 A is the body of the coach; B, the stove, usually placed in one end of the coach; C, the heating-coil, into the lower leg, C², of which the cool water from the returns is received, then heated, and finally discharged through 40 the leg C' into the respective systems of circulation-pipes.

D is the pipe taking water from the heating-coil to the short circuit leading to the radiators under the seats upon the side of the 45 coach next the stove, and D' the return-pipe for the same circuit, taking the cooled water from the radiators back to the heating-coil.

E is the pipe taking water from the heating-coil to the long circuit leading to the radiators under the seats upon the side of coach

opposite to the stove, and E' the return-pipe conducting the cooled water from the radiators back to the heating-coil.

The pipes D and D' and the connected radiators of the short circuit and the pipes E 55 and E' and the connected radiators of the long circuit constitute the double circulation.

F is a pipe leading to the expansion-chamber F', and connecting said expansion-chamber with the heating-coil through the fittings 60 G G' and short nipple C³. The expansion-chamber F' is provided with the usual cock, f, nozzle f', and relief-valve f'', to avoid over-pressure.

G G' are what I term "special" fittings, and 65 consist, in the illustration, of T's in the branch of fitting G, of which I cast a diaphragm, g, as shown in section in Fig. 3, through which diaphragm an orifice, g', is cored or drilled, and in the run of fitting G', I cast a diaphragm, g², 70 provided with an orifice, g³. The orifice g' in fitting G is so proportioned (in relation to the orifice of pipe E) to the length of short circuit D D' and connected radiators and to the difference of heads on pipes D and E as to cause 75 the same amount of hot water to pass through the short circuit as flows into pipe E and around the long circuit.

In the construction of hot-water warming apparatus for railway-coaches it is desirable 80 to have pipes D D' E E' and coil C of uniform diameters, whence if fitting G were unprovided with the diaphragm g and reduced orifice g' considerably more water would pass from the coil C through the short circuit than 85 through the long circuit, whereas by giving the orifice g' the proper area in relation to area of pipe E equal quantities of water are caused to flow through the two circuits, respectively. The reduced opening in fitting G' connects the 90 coil C (as before mentioned) with the expansion-chamber F', whereby the efflux of water at increased temperature from the coil C and system of circulation-pipes to the expansion-chamber and return of water from the ex- 95 pansion-chamber to the coil C and system of circulation-pipes to supply a reduction of volume by diminution of temperature or by leakage are provided for. The orifice g³ also permits the escape of vapor and air-bubbles 100

from the coil C upward into the expansion-chamber F'.

H is a pump connected with the lower leg of the coil C for supplying water to the coil 5 and circulation-pipes while the coach is in motion, the novelty and functions of which are made the subject-matter of another application for patent contemporaneous with this, Serial No. 113,478.

10 I is the bifurcated fitting shown in section in Fig. 4, provided with a central diaphragm or fixed tongue, *i*, which maintains the integrity of the respective returns from pipe D' E' until they are fairly discharged into nipple *i'* which 15 is connected to the lower leg of coil C through elbow I.

The peculiar construction of the fitting I is such that I am enabled to work two separate circuits of hot water with one heating-coil—a 20 result, so far as I am aware, never heretofore accomplished in railway-cars.

The fitting I is equivalent to two elbows placed back to back with a single threaded orifice upon the upper side and two threaded 25 orifices disposed equally right and left of the central diaphragm, *i*.

The general operation of the apparatus, so far as it relates to the heating of the water in the coil C and transfer of it (water) around 30 the coach, is so fully described in my previously-mentioned patent that a detailed description of the same in this specification is omitted.

Fig. 6 shows the application of my special fittings, G G', which are here shown as crosses 35 detailed in section in Fig. 5, to the warming apparatus of a building, the proportions of orifices *g'* in diaphragm *g* being adjusted to the length of radiating-pipes to be supplied with hot water and to the heads on said orifices, 40 the greater the head the smaller the orifices, and the greater the length of circulation and number of radiators the larger the orifices, and vice versa, in the several circuits D of this figure.

By the omission of fitting G and pipes D D', 45 and the substitution of a common elbow for the fitting I, a single circuit of hot water entirely around the car may be maintained, the action being substantially the same as for what is termed the "long circuit" in my former 50 patent mentioned.

I am aware that prior to my invention a T-coupling has been constructed with an internal curved diaphragm for dividing a current of steam or other fluid; but such feature is not 55 broadly claimed by me.

Having described my invention, what I claim, is—

1. The combination of fittings G G', provided with diaphragms *g g'* and orifices *g' g'*, 60 with the coil C and leading-pipes D and E and expansion-chamber F' of a hot-water warming apparatus for railway-cars, when arranged and operating substantially as and for the purpose described.

2. The combination of coil C, fittings G G', having the perforated diaphragms *g g'* and the elbow I, with the pipes D D' and E E', constituting the short and long circuits of a hot-water warming apparatus for railway-cars, 70 when arranged and operating substantially as and for the purpose described.

3. The combination of fitting G', provided with a diaphragm, *g'*, and orifice *g'*, with the coil C, expansion-chamber F', pipes E E', and the customary heat-radiators under the car-seats, to form a single circuit for the hot water in the warming apparatus of railway-cars, 75 when arranged and operating in the manner substantially as described.

In testimony whereof I have signed my name to the foregoing specification in the presence of two subscribing witnesses.

JOHN Q. C. SEARLE.
